United States Patent Office.

W. C. SMITH, OF WARRENSBURG, MISSOURI.

Letters Patent No. 65,702, dated June 11, 1867.

IMPROVED SUGAR-EVAPORATOR.

The Schedule referred to in these Letters Patent and making part of the same.

TO ALL WHOM IT MAY CONCERN:

Be it known that I, W. C. SMITH, of Warrensburg, in the county of Johnson, and State of Missouri, have invented a new and improved Sugar-Evaporator; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and improved sugar-evaporator, designed more especially for evaporating the sirups of northern canes, and to admit of the work being done in a perfect manner by persons of ordinary ability. In the accompanying sheet of drawings—

Figure 1 is a side sectional view of my invention, taken in the line *xx*, fig. 2; and

Figure 2 a plan or top view of the same, with the pans removed.

Similar letters of reference indicate corresponding parts.

A represents the body of the device, which may be constructed of sheet iron, and the fire-box, B, may be constructed of cast-iron plates, and furnished with a grate to support the wood. The device is mounted at one end on two wheels, C C, and supported at the opposite end by two legs or standards, D D, the latter being so arranged and applied that they may be folded back out of the way when necessary. The wheels C C have their bearings in bars or rods, E E, formed out of a single bar, and fitted in bearings, *a*, underneath the body A, and bent in rail form at the front end of the latter, to serve as a convenient handle. By this arrangement the wheels C C, when the device is to be rolled or moved from place to place, may be drawn forward under the edge of the fire-box, so as to render the transportation more easy. On the top of the body A there are placed three pans, F G H, so arranged, one a trifle higher than the other, that the contents of the more elevated pan, F, may be drawn off into the pan G, and from G into the pan H, as will be fully understood by referring to fig. 1. In the body A there is placed a partition, I, above which and the pans there is a space for the flues J J' J'. The most elevated pan, F, is directly above the fire-chamber, B, which may be made to communicate directly with the smoke-stack K, when required, by opening a damper, L, as shown clearly in fig. 1. In the space above the partition, I, directly under the pan, F, there are placed two dampers, M M, pivoted as shown at *b b*, and connected by a rod, *c*, in such a manner that, by moving one of the dampers by means of a rod, *d*, the front and rear ends of the dampers may be moved towards and from each other, and the dampers adjusted in either of the two positions shown in black and red in fig. 2. In the partition, I, directly over the fire-chamber B, there is a damper, N, opening upward, and in the central flue J there are two dampers O O, pivoted as shown at *e e*, and connected by rods *f f* to a crank, *g*, on a shaft, *h*, as shown in fig. 2. The dampers O O are directly under the pan G, and by turning the shaft *h* said dampers may be adjusted in either of the two positions as shown in black and red in fig. 2. The bottom of the body A is formed concave, so as to receive a cooler, P, into which the contents of the lower pan H are discharged through a spout, *i*. This cooler has a free circulation of air all around it. The uppermost pan F is supplied with the juice, and after the fire is well under way the damper L is closed and the damper N raised, and the dampers M M adjusted as shown in black in fig. 2, and the products of combustion will pass from the fire-chamber up through damper N between the dampers M M, and thence into the smoke-stack K, the heat being brought in direct contact with the bottom of pan F. When the juice in this pan is raised to the desired temperature the heat is turned off, by opening the damper L and closing damper N, the draught of the fire being checked in order to avoid the unnecessary consumption of fuel by closing the draught-damper of the ash-pit. After the juice in pan F has settled it is drawn off into the pan G, through a spout, *j*, which may be provided with a strainer, in order to prevent any sediment passing into G. The pan F is now refilled with fresh or crude juice, and after the juice is neutralized in G, the boiling in both pans, F G, may be proceeded with without heating the lower pan, H, by adjusting the dampers O O as shown in black in fig. 2, so that the products of combustion will pass into flue J, and through openings *k k* in the partitions which form the flues J J' J', into the flues J', and thence into the smoke pipe, as indicated by the red arrows. When the juice after the second filling of the pan F has reached the desired temperature, the dampers O O are adjusted in a parallel position, as shown in dotted lines,

and the products of combustion made to pass under both pans G H, as indicated by the blue arrows. By this arrangement all the pans may have their contents in a boiling state at the same time, and the heat under the highest pan, F, may be graduated as desired by adjusting the dampers M to a position between the extreme points of their movement. When the syrup is boiled to a proper consistency in the pan H, the former is drawn off into the cooler P through tube i.

I do not claim, in a sugar-evaporating apparatus, the employment or use of a series of pans arranged at different heights, for they have been previously used, but I do claim as new, and desire to secure by Letters Patent—

The pans F G H, arranged at different heights on the body A of the device, when used in combination with the flues J J' J', dampers M M N O O, arranged relatively with the smoke-stack K and fire-box B, substantially as and for the purpose set forth.

I further claim the adjustable wheels C C, and folding legs or supports D D, when used in combination with or applied to a sugar-evaporator, substantially as and for the purpose specified.

W. C. SMITH.
